UNITED STATES PATENT OFFICE

ARTHUR C. CHANDLER, OF TORONTO, ONTARIO, CANADA

EXTENSION TABLE FOR CABINETS

Application filed February 13, 1930. Serial No. 428,180.

The principal objects of this invention are to devise an extension table construction which may be applied to desks or cabinets, which may be housed within the cabinet or 5 extended therefrom to project so as to extend over a bed or a chair and which may be adjusted to various heights.

The principal feature of the invention consists in the novel construction of a slidable 10 frame and its arrangement within a cabinet whereby a hinged table carried by the frame may be supported in a raised position extended from the cabinet or may be housed within the cabinet.

15 In the drawings, Figure 1 is a perspective view of a cabinet to which the present invention is applied showing the extension table in a raised and extended position.

Figure 2 is a vertical cross-sectional view 20 through the cabinet showing the extension table raised.

Figure 3 is an enlarged elevational view 25 of the hinged portion of the extension table and its support.

Figure 4 is a side elevational sectional view 30 showing the table in the extended position.

Figure 5 is a side elevational sectional detail showing the table in the housed position.

In the application of the invention herein 35 shown, the cabinet 1 is provided with a vertical pocket 2 arranged at one side thereof which is open at the top and a slidable cover 3 arranged on top of the cabinet is adapted to close the pocket and may be moved longitudinally to uncover the top of the pocket.

An inverted U-shaped metal frame 4 is vertically arranged within the pocket 2 and slidably supported in brackets 5 secured to the front and back walls thereof.

40 The lower ends 6 of the frame 4 are turned inwardly and rods 7 are rigidly mounted between the ends 6 and the cross top of the frame. These rods are parallelly arranged and form the guides for a pair of bracket members 8 which are slidably mounted thereon.

A table member 9 provided with hinge brackets 10 secured at one edge thereof is pivotally supported from the brackets 8 and 50 when the table is in the position shown in

Figures 1 and 4, the members 10 rest upon the top of the frame 4 and support the table in a horizontal position.

A bar 11 rigidly secured to the top bar of the frame 4 centrally of its width extends downwardly and is slidably mounted in a tubular standard 12 secured within the pocket 2 of the cabinet close to the end wall. 55

The bar is formed with a plurality of ratchet notches 13 which are engaged by a latch member 14 pivotally supported on the standard. 60

A rod 15 connected to the latch member extends horizontally through a hole in the front wall of the cabinet and is provided with an operating knob 16 on its outer end. A coil spring 17 encircles the rod 15 and holds the latch member in constant engagement with the notched bar 11. 65

The frame 4 and the rods 7 forming a part therewith slide freely vertically of the cabinet and when the cover is moved back to uncover the top of the pocket 2, the frame may be raised to any desired position and it will be held in the raised position by the latch member 14 engaging the ratchet bar 11. 70

The table 9, which when the device is arranged within the pocket, is supported in a vertical position is, upon the raising of the frame, swung over the top thereof into the 80 position shown in Figures 1 and 4.

A table such as described will be very easily handled by a nurse attending a patient and even though she may be carrying a tray, she can slide the table top back clear of the 85 pocket, raise the table frame, swing the table top into position with one hand quite readily. When the table is not required it is swung from its horizontal position and simply by pulling out on the knob 16 and releasing the ratchet bar 11 the frame and table top may be lowered into the retaining pocket, which is then covered over by the sliding table top.

The device is extremely simple and details 90 of the construction may be altered without departing from the spirit of the invention.

What I claim as my invention is:

1. An extension table having vertical 100 guides, a member vertically slidable in said

- guides, a table member and means pivotally and slidably connecting said table member to said slidable member, said vertically slideable member having means for engaging said table top and said connecting means to support the table in an extended position. 5
2. A cabinet having a vertical pocket open at the top, a cover for said cabinet slidably thereon to cover said pocket, a frame slidably arranged in said pocket, and a table having support members interposed between itself and said slideable frame, said support members being slideable on said frame and pivotally connected with the table whereby the latter may be extended or swung relative to said frame. 10
3. A cabinet having a vertical pocket therein open at the top, a frame slidably mounted and adapted to extend out of said pocket, means for holding said frame in adjusted positions, support members slidably mounted on said slideably mounted frame for movement from end to end thereof, and a table pivotally mounted on said support members to be extended outwardly therefrom. 15
4. A cabinet, comprising a stand, a member vertically slideable in said stand and adapted to extend thereabove and having bracket members slideable vertically thereon, and a table pivoted at one end on said bracket members and adapted when said slideable brackets are moved to the top of said vertically slideable member to be swung outwardly over the latter and extend in a rigid horizontal position from the top thereof. 20
5. A cabinet having a rigid U-shaped frame the side members of which are slideably supported therein, guide bars carried by said U-shaped frame, brackets slideably mounted on said guide bars, a table member hinged to said brackets and adapted to be swung over the frame, said frame engaging the table member to support the table in a horizontal position, and means for holding said frame in adjusted positions. 25
6. A cabinet comprising a member vertically slideable in said cabinet, a table hinged to said member and adapted to extend in a horizontal position, a ratchet bar rigidly secured to said slideable member, guide means for said ratchet bar, a latch member pivotally mounted within the cabinet and engaging said ratchet bar, a rod pivotally connected to said latch member and extending outwardly through the wall of the cabinet for releasing said latch, and a coiled spring encircling said rod within the cabinet and exerting an inward pressure on said rod to hold said latch normally in locking position. 30
7. A cabinet having a vertical pocket in one end open at the top, brackets mounted in said pocket, a U-shaped metal frame slideable in said brackets, bars rigidly secured in said U-shaped frame and arranged parallel with the sides thereof, bracket members slidably mounted on said bars, bracket members hinged to the aforesaid brackets, a table top secured to the latter brackets and adapted to rest upon the top of the U-shaped frame when in the extended position, and means for holding said U-shaped frame and table supported thereby in adjusted positions. 70
8. In an extension table, a base, an inverted U-shaped frame having its side members slideably mounted in said base and having the lower end extremities turned laterally inward, guide rods secured at their lower ends in said laterally turned portions and at their upper ends in the connecting top portion of said frame, a table top having a combined pivotal and slideable mounting on said guide rods and adapted to be swung outward from the top part of said frame, and means for supporting said inverted U-shaped frame in adjusted positions. 75
9. In an extension table, a base, an inverted U-shaped frame having its side members slideably mounted in said base, parallel guide rods mounted in said U-shaped frame and spaced from the side members thereof, a notched rod secured at its upper end centrally of the top part of said U-frame, guide means carried by said base for guiding the lower free end of said notched rod, manually operable latch means co-operating with said notched rod, and a table top having a combined pivotal and slideable mounting at one end on said guide rods. 80
10. In an extension table, a cabinet, a frame adapted to be housed in said cabinet and extensible therefrom, support members slideably mounted on said extensible frame, a table top mounted on said support members, and a pivotal joint interposed between said table top and support members, whereby said table top may be housed in the cabinet alongside said frame or may be extended relative thereto and turned laterally therefrom on its pivotal joint, and means for supporting said extensible frame in various extended positions. 100
11. In an extension table, a cabinet, a frame adapted to be housed in said cabinet and vertically extensible therefrom, a table top having means pivotally connected therewith and vertically adjustable on said frame whereby the table may be raised or lowered relative thereto to remove it from or return it to the said cabinet, said table top when returned to the cabinet occupying a position at one side of said extensible frame, the pivotal connection of said table with said vertically slideable means permitting it to be swung over said frame and to extend to the opposite side of the frame, and means for supporting said extensible frame at various heights. 115
